UNITED STATES PATENT OFFICE.

WILLIAM A. KNOWLES, OF ALAMEDA, ASSIGNOR TO EDGAR THOMPSON, OF SAN FRANCISCO, CALIFORNIA.

DENTAL-ENGINE BRACKET.

SPECIFICATION forming part of Letters Patent No. 368,154, dated August 9, 1887.

Application filed November 30, 1886. Serial No. 220,242. (No model.)

To all whom it may concern:

Be it known that I, WILLIAM A. KNOWLES, a citizen of the United States, residing in Alameda, in the county of Alameda and State of California, have invented a new and useful Dental-Engine Bracket, of which the following is a specification.

My invention relates to dental engines for drilling and other purposes; and it consists in the features of construction and combinations of parts hereinafter fully described and claimed.

In the drawings which form part of this specification, Figure 1 is a side elevation, partly in perspective, of a dental engine embodying my invention. Fig. 2 is a plan view of the same. Fig. 3 is a longitudinal vertical section illustrating the means of attaching the engine to the wall of the room or any desired object. Fig. 4 is a detail sectional view. Fig. 5 is a detail view of the jointed post and guide-sleeve, and Fig. 6 a detail perspective view showing the device employed for keeping the driving-cord taut and regulating the tension of the latter.

Corresponding parts in the several figures are denoted by the same letters of reference.

Referring to the drawings, A represents a plate designed to be secured to a wall and having perforated lugs a.

B represents a bracket, which is provided with perforated lugs connected by means of pintles b to the lugs a, whereby said bracket is pivoted in place.

C represents a sleeve, which is secured to the lower end of the bracket B, and has near its outer end a clamping-collar, c, in an opening of which is seated a set-screw, d.

D represents a brace-rod, which extends from the upper end of the bracket B to the collar c, to which it is secured, and which serves to support and hold the outer end of the sleeve C in a horizontal position.

E represents a tubular post secured to the outer end of the sleeve c, and secured to the upper end of the tubular post E is a bracket, G, which has upwardly-extending perforated ears or lugs, between which are journaled pulleys g g', and on the upper end of the shaft F are mounted pulleys h h'.

H represents a tubular support secured in

the bracket G, near the outer end thereof, and having within it a spiral spring, i.

I represents a tube or pipe, which is provided about midway its length with a slot, j. This tube I has its lower end resting on the spring i and has its upper end extending beyond the support H.

J represents the drill-head post, which consists of a head, J', and a post, J'', jointed together, as at j, the joint being located in the tube I, so that the head J' is held in a vertical position. A set-screw, k, passes through the support h, the slot j, and an opening in the post J'', and bears against the interior surface of the tube I.

K represents a pulley having bearing in the head J', and fitting in an opening in the pulley is a drill-spindle, L, carrying the usual drill and inclosed by a sleeve, M. The drill when not in use is designed to be supported by a hook, l, secured to the sleeve c.

N represents a cord connecting the pulleys K and h', said cord passing around the pulleys g and g' and through guides m in the tube I.

P represents a cord passing around the pulley h and over pulleys u u', journaled upon the bracket B. Below the latter are secured to the wall of the room or suitable object brackets Q Q'. The bracket Q is provided with a box, Q², to the ends of which are journaled pulleys Q³ Q⁴. Secured to said box Q² at its lower end and to the bracket Q' at its upper end is a rod, R, on which is a spiral spring, S.

T represents a collar located on the rod and clamped at any desired adjustment by a set-screw, r. The collar T is formed with a box, U, which has pulleys V V' journaled to its ends. The cord P, after passing over the pulleys u u', is carried down under the pulleys Q³ Q⁴, up over the pulleys V V', and then down. It may then be passed around a band-wheel operated by a treadle or otherwise. (Not shown.)

It will be seen that by moving the collar T upwardly the cord P will be tightened. When it is desired to extend the operating mechanism, the collar T is moved downwardly, thus loosening the cord P. The sleeve c may then be drawn out of the sleeve C the desired distance and clamped in its adjusted position by the set-screw.

Having thus described my invention, what I claim as new, and desire to secure by Letters Patent, is—

1. The combination, with a stationary sleeve, 5 of an adjustable sleeve, a tubular post, E, secured to said adjustable sleeve, a shaft in said post, said shaft carrying pulleys, a bracket, G, on the shaft F, a tubular support, H, secured to the bracket G and having a spring, i, the 10 slotted tube I, the drill-head post consisting of two parts jointed together and adapted to support drilling mechanism, substantially as set forth.
2. The combination, with drilling mechanism and its supports, of the pulleys K g g' h h' 15

u u', the operating-cord P, a rod carrying a stationary pulley, and the box vertically adjustable on said rod and carrying pulleys V V', as set forth.

3. The combination, with a tubular support 20 and a spring in the bottom thereof, of a vertically-adjustable sleeve located in said support, a drill-head post located in said sleeve, and a drill-head jointed to said post, substantially as described.

WILLIAM A. KNOWLES.
